UNITED STATES PATENT OFFICE.

HERMANN G. MUENCH, OF BERKELEY, CALIFORNIA.

BOTTLE-LABELING MACHINE.

1,047,550.

Specification of Letters Patent. Patented Dec. 17, 1912.

Application filed January 18, 1912. Serial No. 671,815.

To all whom it may concern:

Be it known that I, HERMANN G. MUENCH, a citizen of the United States, residing at Berkeley, in the county of Alameda and State of California, have invented new and useful Improvements in Bottle-Labeling Machines, of which the following is a specification.

This invention relates to a labeling machine, and particularly pertains to a machine for automatically placing labels on bottles and the like.

It is the object of this invention to provide a bottle labeling machine, which is simple in construction and efficient in operation, compact in form and adapted to be operated at high speed.

Another object is to provide a bottle labeling machine which is so arranged that labels may be placed on the neck and body portions of a bottle simultaneously, and in which the labels will be placed on the bottle without mutilation.

Other objects will appear in the following specification.

The invention consists of the parts and the construction and combination of parts as hereinafter more fully described and claimed, having reference to the accompanying drawings in which—

Figure 1 is a side elevation of the invention with parts broken away. Fig. 2 is a longitudinal vertical section of the bottle labeling portions of same. Fig. 3 is a horizontal section on the line W—W of Fig. 2. Fig. 4 is a detail in elevation of the paste distributing roller. Fig. 5 is a detail in plan of the label feeding mechanism. Fig. 6 is an enlarged horizontal section on the line X—X of Fig. 40 1. Fig. 7 is a detail in elevation of one set of the label wipers. Fig. 8 is a detail in elevation of the device for holding the labels in position on the bottle. Fig. 9 is a detail in elevation of a portion of the label-holder for 45 positioning the labels on the bottle.

In the drawings, A represents the frame of the machine which may be of any suitable construction, and 2 indicates a horizontally disposed endless belt carried on rollers 3—3' journalled on the frame A; the upper wing of the belt traversing and supported by a table top B formed on the frame A. A gear 4 attached to the roller 3 meshes with a pinion 5 on a shaft 6 which has a pinion 7 meshing with a gear 8 mounted on a drive shaft 9 journalled on the lower portion of the frame

A, as shown in Fig. 1. The drive shaft 9 is designed to be driven continuously from any suitable source of power through a belt pulley 10, thereby transmitting continuous rotary motion to the roller 3 through the gears 8—7—5—4 to drive the belt 2 continuously. Formed on the belt 2 centrally thereof is a series of semicircular flanges 11, spaced any suitable distance apart which are designed to receive the lower ends of bottles C to be labeled, as shown in Figs. 1, 2 and 6.

Mounted on the table top B is a pair of spaced, vertically disposed guide rods 12, one of which is positioned on each side of the conveyer belt 2, as shown in Fig. 6, and mounted on each of the guide rods 12 is a sleeve 13, which sleeves are designed to be reciprocated in unison with each other and intermittently by means of a mutilated gear 14 mounted on the drive shaft 9; the gear 14 being adapted to be engaged with and disengaged from, a gear 15 mounted on a shaft carrying a disk 16 on which a wrist pin 17 in engagement with a connecting rod 18 is mounted. The connecting rod 18 is pivoted to a cross head 19 which connects at its outer ends with pitman rods 20 leading to, and connected with, trunnions on the sleeves 13, as shown in Figs. 1, 2 and 6. 85 Mounted on the sleeves 13 and extending inwardly therefrom and projecting over the belt 2 is a pair of superposed gates 21—21'. The gates 21—21' normally extend in the path of travel of the bottles C carried on the belt 2, as shown in Fig. 6, when the sleeves 13 are in their lowermost positions, and are normally retained in their innermost positions by means of springs 22. The gates 21—21' constitute label carriers and are 90 provided for the purpose of positioning pasted labels in the path of travel of the bottles C, as will presently be described; the labels being delivered to the gates 21—21' by means of a label feeding mechanism disposed adjacent the upper ends of the guide rods 12.

The label feeding mechanism is here shown as consisting of a horizontally reciprocable carriage 23 having a pair of 105 superposed label-receiving chambers, on each of which a quantity of the labels to be fed to the gates 21—21' is disposed in a vertical position. The carriage 23 is positioned between the guide rods 12 a short 110 distance rearward thereof and is slidably mounted on horizontally extending rods 24

supported on the rods 12 and an upwardly projecting portion of the machine frame, indicated at D, mounted on the table top B. The carriage 23 is designed to be reciprocated intermittently by means of a lever 25 which is fulcrumed at 26 on the frame D and has its lower end projecting in the path of travel of a cam or finger 27 carried on a gear 62 loosely mounted on, and adapted to be rotated by, a shaft 28, as later described. The shaft 28 is journaled in suitable bearings on the frame D and is continuously rotated by means of a sprocket chain 29 from the roller 3; sprockets 30—30' being provided on the shaft 28 and roller 3, as shown in Fig. 1, with which the chain 29 is engaged. Mounted on the shaft 28 in alignment with the vertical path of travel of the gates 21—21' is a pair of paste-feeding rollers 32 which extend into a paste receptacle 33 carried on the frame D. Paste-delivering rollers 34 normally contact the peripheries of the feeding rollers 32 and are mounted on bell-crank levers 35, pivoted at 36 on the frame D, as shown in Figs. 2, 3 and 4.

The bell-crank levers 35 are designed to be rocked by means of fingers 37 carried on the shaft 28, which fingers engage the lower arms of the bell-crank levers 35, as the shaft 28 revolves, in such manner as to rock the bell-crank levers 35 and thereby throw the rollers 34 out of contact with the rollers 33 and dispose them in the path of travel of the outer faces of the gates 21—21'; springs 38 acting on the bell-crank levers 35 to restore them to their normal position when released from the fingers 37.

In the operation of the label feeding, 40 pasting and delivering portions of the invention just described, the gates 21—21' are caused to move upward by the action of the constantly rotating mutilated gear 14, which meshes with the pinion 15 when the sleeves 13 and the gates 21—21' thereon are in the lowermost positions; the gear 15 being rotated to rotate the disk 16 one-half of a revolution during a portion of a revolution of the mutilated gear 14. The disk 16 in 45 traversing one-half of a revolution causes the sleeves 13 and gates 21—21' to move upward by means of the wrist pin 17 and the connecting rods 18 and 20. As the gates 21—21' are moved upward, the paste-distributing rollers 34 are moved by the action of the fingers 37 into such position as to cause them to roll over the outer face of the gates 21 and 21', and thereby coat these faces with a suitable quantity of paste. 50 This being done, the rollers 34 are moved out of the path of travel of the gates 21 and 21' by the springs 38; the gates continuing their upward movement until their uppermost position is reached, whereupon they are 55 caused to become stationary by reason of the

70 mutilated gear 14 being disengaged from the gear 15. The moment the gates 21—21' are in their uppermost position, the carriage 23 is advanced by means of the finger 27 on the shaft 28 acting on the lever 25, to press the outermost label against the pasted faces of the gates 21—21'. The end of the carriage 23 facing the gates 21—21' is open, so that practically the entire rear face of the label is exposed; spring fingers 39 engaging the upper edges of the outermost labels, as shown in Fig. 2. The carriage 23 is then moved rearward by means of a spring 40 acting on the lever 25 to restore the carriage 23 to its normal position. The carriage 23, in moving backward, leaves the outermost labels sticking to the pasted outer faces of the gates 21—21'. The gates 21—21' carrying the labels are now caused to be restored to their lowermost position by reason of the mutilated gear 14 again meshing with the gear 15. The labels carried on the gates 21—21' are thus disposed across the path of travel of the bottles C; the labels on the gates 21 being positioned in front of the body portion of the bottles while the label on the gates 21' is positioned in front of the neck portion of the bottle. The gates 21—21' with the labels thereon are held stationary in the lowermost position for a short time by reason of the mutilated gear 14 disengaging from the gear 15, and during the time the gates 21—21' are in their lowermost position, the bottle C is carried forward on the belt 2 between the gates 21—21', thereby swinging the gates on their hinges in the direction of the arrows a, in Fig. 6, thus causing the labels to be removed from the gates and adhered to the bottle; the gates being restored to their normal position after the bottle C has passed therebetween, by means of the springs 22, after which they are again operated, as just described, to position another set of pasted labels in front of the succeeding bottle on the belt 2. 100

105 Means are provided for continuously advancing the labels in the carriage 23, and this means is here shown as consisting of slideable blocks 40' mounted on the carriage 23 and caused to bear against the forward ends of the stacks of labels, by means of springs 41 which bear between the blocks 40' and collars formed on set-screws 42 mounted in a gate 43 secured to the carriage 23, as shown in Fig. 2. By adjusting the 110 set-screws 42, tension may be maintained on the springs 41, thereby exerting continuous pressure on the slideable blocks 40', as the labels are removed.

115 Means are provided for holding the label against the bottle, as the latter passes between the gates 21—21', and for wiping the labels smoothly around the face of the bottle to insure their adhering thereto. The label wiping means consists of flexible wipers 44 120

5 mounted to flex horizontally; these wipers extending in the path of travel of the bottles adjacent the gates 21-21' in such position as to bear against the labels the moment the latter are disengaged from the gates 21-21'.
The bottle, in passing between the wipers 44, causes the latter to press the pasted edges of the labels tightly and smoothly against the sides of the bottle.

10 The mechanism for holding the labels in position on the bottle and preventing their shifting thereon during the smoothing action of the wipers 14 consists of a pair of vertically disposed, superposed rollers 45-45', which are so mounted as to contact the labels 15 on the gates 21-21' respectively and hold them against the bottle, as the latter passes between the gates 21-21'. The roller 45 is journaled on a frame 46 mounted to move 20 horizontally on a standard 47; studs 48 on the frame 46 extending through perforations in the standard 47 and slideable therein, as shown in Fig. 8. Helical springs 49 wound on the studs 48 bear between the 25 standard 47 and the frame 46 to normally retain the latter in its forwardmost position; nuts 50 on the outer ends of the studs limiting the forward movement thereof. The roller 45' is journaled on the upper end of the standard 47, which is curved to dispose 30 the roller 45' in vertical alignment with the roller 45.

35 The standard 47 is mounted on an arm 51 which extends transverse of the belt 2 and is 40 slidably mounted on an arm 52 extending parallel with the belt 2 adjacent one edge thereof, as shown in Fig. 6. The arm 52 is mounted to swing horizontally, being pivoted at 53, and is normally held in its innermost 45 position parallel with the line of travel of the belt 2 by means of a spring 54. A pin 55 on the table top B limits the forward movement of the arm 52, due to the action of the spring 54. The spring 54 also acts on the arm 51 to normally retain it in its innermost 50 position on the arm 52, in which position the rollers 45-45' will be disposed against the outer face of the labels on the gates 21-21', as shown in Fig. 6. The body portion 55 of the bottle C, in passing between the gates 21 bears against the label thereon and presses it against the roller 45; the latter moving backward with the bottle on the standard 47 in opposition to the spring 49, until the neck of the bottle, which is offset from the body of the bottle, contacts the label on the gate 21' and presses it against the roller 45'. When this occurs, the continued 60 movement of the bottle acts to slide the arm 51 lengthwise of the arm 52, thus pinching the labels between the neck and body portions of the bottle and the rollers 45-45', and securely holding them against shifting sidewise when acted on by the wipers 44. The arm 51 is carried lengthwise

of the arm 52 until the wipers 44 leave the labels on the bottle, whereupon a wedge 56 on the arm 51 engages the pin 55 in such manner as to rock the arm 52 a short distance and thereby throw the rollers 45-45' 70 to one side of the center of the bottle; whereupon the continued movement of the bottle will cause the body portion thereof to act to force the roller 45 to one side. This has the effect of rocking the arm 52 into the position 75 indicated in dotted lines in Fig. 6, and allows the bottle to pass beyond the rollers 45-45', whereupon the latter are restored to their normal position by the action of the spring 54, which operates to rock the arm 52 to its 80 normal position and move the arm 51 on the arm 52 back to its normal position, indicated in full lines in Fig. 6, against the label previously positioned in readiness to be wiped on the next bottle. The wipers 44 are sufficiently separated from each other at their ends to allow the rollers 45-45' to pass therebetween on their return to their normal 85 position.

90 Means are provided for holding the bottle in an upright position as it passes between the gates 21-21' and the wipers 44. This means is here shown as consisting of a mechanism adapted to be engaged with the upper ends of the bottles as they pass between the gates 21-21', and disengaged therefrom after the bottle has passed between the wipers 44. This mechanism consists of a rod 57 slidably mounted on a revoluble shaft 58 at right angles thereto; the shaft 58 being journaled on the frame D above the wipers 44 and the rod 57 located thereon in alignment with the path of travel of the upper ends of the bottles. The outer ends of the rod 57 project beyond opposite sides of the shaft 58 and have pockets 59 mounted thereon which are adapted to receive the upper ends of the bottles, as shown in Fig. 2. Helical springs 60 are wound on the rod 57 on each side of the shaft 58 to normally retain the rod 57 in a central position under tension in both directions. The shaft 58 has a gear 61 thereon, which meshes with the gear 62 on the shaft 28. The gear 62 is designed to be thrown in and out of operative 105 connection with the shaft 28 by means of a clutch member 63 splined on the shaft 28, which clutch is operated by a lever arm 64 on a vertical rock shaft 65. The shaft 65 is rocked intermittently by means of a lever 110 arm 66 thereon, the outer end of which extends in the path of travel of the bottles on the belt 2 in such manner that it will be rocked a short distance by the bottle to throw the clutch member 63 on the shaft 28 115 120 into engagement with a clutch member 67 on the gear 62.

125 The clutch members 63-67 will be held in engagement with each other during the time the bottle is passing the outer end of the lever 130

arm 66, so as to rotate the gear 61 and the shaft 58 one-half of a revolution, whereupon the clutch member 63 is thrown out of engagement with the clutch member 67 by 5 means of a spring 68 acting on an arm on the rock shaft 65. The rotation of the shaft 58 is so timed that it will come to a stop when the rod 57 is in the position shown in full lines in Fig. 2, in which position the 10 pocket 59 on one end thereof will be so disposed that the upper end of the bottle about to pass between the gates 21-21' will enter therein. The shaft 58 is then rotated so that the pocket 59 will move forward with the 15 bottle A; the rod 57 moving upward and downward as the bottle passes under the shaft 58. The shaft 58 is rotated after the pocket 59 is released from the bottle top a sufficient distance to dispose the pocket 59 20 on the other end of the rod 57 in such position as to engage the top of the succeeding bottle. The bottle may be fed to, and removed from, the belt 2 in any desired manner.

25 It will be seen that the gear 62 will be rotated only when the lever arm 66 is actuated and, as the operation of the lever arm 66 is controlled by a bottle being carried forward on the belt 2, the rotation of the shaft 30 58 and the reciprocation of the label-carrying carriage 23 will take place only when a bottle is positioned on the belt 2 to actuate the lever arm 66. By this arrangement the labels will not be fed to the gates 21-21' 35 unless a bottle is delivered to the machine to receive it.

I do not desire to be understood as limiting myself to the details of construction and arrangement as herein described and illustrated, as it is manifest that variations and modifications may be made therein in the adaptation of the device to various conditions of use without departing from the spirit of my invention, and I therefore 40 45 reserve the right to all such variations and modifications as properly fall within the scope of my invention and the terms of the following claims.

Having thus described my invention, what 50 I claim and desire to secure by Letters Patent is—

1. The combination in a labeling machine, of a bottle carrier, means for operating the same, means for positioning a label in the 55 path of travel of a bottle on said carrier, including parallel, vertically movable gates hinged to swing horizontally, means for operating the gates, means for holding a label against the bottle, and means for wiping the label on the bottle as the latter is 60 advanced by the carrier.

2. In a labeling machine, a bottle conveyer comprising an endless belt, means for rotating same, means for positioning a label 65 in the path of travel of a bottle on said con-

veyer, including parallel, vertically movable gates hinged to swing horizontally, means for reciprocating the gates, means for delivering a label to said gates, means for holding the positioned label against a bottle, and means for wiping the label on the bottle as it is advanced by said conveyer. 70

3. In a labeling machine, a bottle conveyer comprising an endless belt, means for rotating same, means for positioning a label in the path of travel of a bottle on said conveyer, including parallel, vertically movable gates hinged to swing horizontally, means for reciprocating the gates, means for delivering a label to said gates, controlled by the bottle to be labeled on said conveyer, means for holding a positioned label against a bottle, and means for wiping the label on the bottle as it is advanced by said conveyer. 75 80

4. In a labeling machine, an endless belt, bottle-holding means thereon, means for rotating said belt, parallel gates hinged to swing horizontally projecting toward each other over said belt, means for reciprocating 90 said gates vertically, means for applying paste to the outer vertical faces of the gates on the upward movement thereof, and means for delivering labels to the pasted faces of the gates, comprising a horizontally reciprocable label-carrying carriage controlled by the bottle to be labeled on said belt. 95

5. In a labeling machine, an endless belt, bottle-holding means thereon, means for rotating said belt, parallel gates hinged to 100 swing horizontally projecting toward each other over said belt, means for reciprocating said gates vertically, means for applying paste to the outer vertical faces of the gates on the upward movement thereof, means for 105 delivering labels to the pasted faces of the gates, comprising a horizontally reciprocable label-carrying carriage controlled by the bottle to be labeled on said belt, means for holding the gates stationary in their lower- 110 most position to dispose the label thereon in the path of travel of a bottle on the belt to allow the moving bottle to remove the label from the gates, and means for wiping the label on the bottle as the latter moves 115 forward.

6. In a labeling machine, an endless belt, bottle-holding means thereon, means for rotating said belt, parallel gates hinged to 120 swing horizontally projecting toward each other, over said belt, means for reciprocating said gates vertically, means for applying paste to the outer vertical faces of the gates on the upward movement thereof, means for delivering labels to the pasted faces of the 125 gates, comprising a horizontally reciprocable label-carrying carriage controlled by the bottle to be labeled on said belt, means for holding the gates stationary in their lower- most position to dispose the label thereon in 130

the path of travel of a bottle on the belt to allow the moving bottle to remove the label from the gates, means for holding the label against the bottle, and means for wiping the label on the bottle as the latter moves forward.

7. In a labeling machine, an endless belt, bottle-holding means thereon, means for rotating said belt, parallel gates hinged to swing horizontally projecting toward each other over said belt, means for reciprocating said gates vertically, means for applying paste to the outer vertical faces of the gates on the upward movement thereof, means for delivering labels to the pasted faces of the gates, comprising a horizontally reciprocable label-carrying carriage controlled by the bottle to be labeled on said belt, means for hold-

ing the gates stationary in their lowermost position to dispose the label thereon in the path of travel of a bottle on the belt to allow the moving bottle to remove the label from the gates, means for holding the label against the bottle, means for wiping the label on the bottle as the latter moves forward, and means for holding the upper end of the bottle while the label is being applied thereto.

In testimony whereof I have hereunto set my hand in the presence of two subscribing witnesses.

HERMANN G. MUENCH.
